UNITED STATES PATENT OFFICE.

FREDERICK C. RIES, OF MACON, GEORGIA.

DENTAL PLUGGER.

SPECIFICATION forming part of Letters Patent No. 425,844, dated April 8, 1890.

Application filed June 5, 1889. Serial No. 313,232. (Model.)

To all whom it may concern:

Be it known that I, FREDERICK C. RIES, of Macon, in the county of Bibb and State of Georgia, have invented certain new and useful 5 Improvements in Dental Pluggers; and I do hereby declare the following to be a full, clear, and exact description of the invention, such as will enable others skilled in the art to which it pertains to make and use it, reference being 10 had to the accompanying drawings, which form part of this specification.

My invention relates to an improvement in dental pluggers; and the objects of my invention are to provide a very small light tool 15 which is adapted to be operated by a motor of any suitable kind, and in which the parts are so constructed that the plunger is not brought into operation until the operator desires; to use both a light and a heavy spring upon the 20 same rod, so as to regulate the force of the blows which are to be given; to increase or decrease the power of the blows at the will of the operator by a mere movement of a thumb-slide, and to provide an extension tool-holder 25 by means of which the ordinary tools are adapted to work upon teeth in the back of the head or mouth.

Figure 1 is a side elevation of a dental plunger, which embodies my invention complete. Fig. 2 is an enlarged side elevation of the operating parts, the side of the casing being removed. Fig. 3 is a detached view of the tool-holder and operating-lever. Figs. 4, 5, 6, 7, 8, and 9 are detail views of the different 35 parts. Fig. 10 is a side elevation of the plunger with the expansion-cover.

C represents the end of the operating-shaft, through which connection is made with the foot-power, the electric engine, or any other 40 motor. This shaft C is journaled in suitable bearings prepared for it in the end of the casing E, and the pinion D may either be made as a part of the shaft or secured thereto, as may be preferred. This pinion D on the 45 shaft C engages with the wheel F, which has an opening with a square shoulder made through its center, and in this opening is placed a plate G, having square edges or flanges to correspond to the shape of the 50 opening through the wheel F. This plate is prevented from revolving by means of the

pins H, which pass into or through the plate I, upon which the plate G is placed. Through the opening in the center of this plate is passed a screw, which serves to secure the 55 plate G rigidly in position, and through the plate to hold the wheel F in contact with the plate I. The wheel F revolves freely around the plate G, as shown, for the purpose of causing the pin J, which projects from its 60 face, to operate the spring-pitman K, which is provided with the arrow-shaped head L. The pitman K is made elastic, so that as the wheel F revolves rapidly around, its pin J will simply force the pitman to one side, so as 65 to allow the pin to pass by without operating the pitman when the operator does not desire the pitman to be brought into play. When the pitman is to be brought into play, and it is moved endwise so as to bring its head L 70 into position, the pin J catches behind the shoulders of the head and moves the pitman endwise as the wheel F is revolved until the end of the head L strikes against the tool-head N, placed inside of the frame just be- 75 yond the edge of the wheel F. When the mallet strikes against the tool-head or lever, all further movement of the pitman is stopped, and then the pin J moves on around, and when it slips from under the end of the head 80 L the pitman is retracted by the two springs P Q, placed upon the rod O. The head N upon the rod O serves simply to hold the pitman K, and nothing more. To opposite ends of the 85 rod O are secured the endwise-moving head N and the mallet.

Placed inside of the casing E is the stationary partition S, through which the rod O passes, and secured to this partition is a curved spring T, as shown in Fig. 6, and which has 90 its outer end to extend straight outward beyond the edge of the partition and through a slot in the casing E, so as to hold the cover U of the casing in position. This cover U has a notch made in its end, and in this notch 95 the projecting point of the spring T catches. When the projecting point of the spring is forced out of the notch by the finger-nail, the cover can be slipped off and the wheel F and other parts will be exposed for lubrication, 100 display, or repairs. This dental plunger can also be fastened to the dental engine in the

same manner as the cover L' is fastened to the dental plugger, using the same spring, notch, and pin.

Placed inside of the casing E, upon the rod O, is the sliding sleeve or collar V, which has a screw-socket formed in one side, and into which socket a screw-threaded portion of the nut W, also loosely placed upon the rod O, screws. This sleeve V and screw W are connected together, and slide back and forth upon the rod O for the purpose of regulating the tension of the springs P Q, and thus regulate the blow which shall be given to the tool while in use upon the filling of the tooth. The nut W, having a roughened surface, has a portion of its surface exposed through a slot X in the casing E, so that the finger of the operator can reach it at any time and thus adjust the tension of the springs P Q at will. The sliding collar V is attached by means of a small wire or rod Y, which passes through a groove Z in the mallet R to the thumb or finger-slide A', so that by the movement of the slide A' by the thumb of the operator he can move the collar V and nut W endwise upon the rod O, and thus increase the tension of the springs P Q at will. The rod or wire is very small and passes inside of the casing E through the groove Z in the mallet to the collar V, as shown.

Inside of the thumb-slide A' is made a button B', which passes through slot C' in the casing E, and which button serves to hold the thumb-slide in position upon the side of the casing E. When the regulating devices are not brought into use, the tension of the strong spring P is not interfered with, but as soon as the thumb-slide, ball, or screw are moved the strong spring P and the weak one Q are compressed between the nut W and the end of the mallet R; hence a stronger blow is necessarily given. The two springs P Q are separated by a loose washer Q'. Two springs of different tensions are used, so that the weaker one will act on the mallet independently of the other, whereby the softest or lightest blows can be obtained. The construction here shown does not admit of lengthening or shortening the stroke of the mallet, and hence the importance of the weaker spring Q.

In the end of the mallet is formed a recess or cavity P', into which the weaker spring Q can be forced by the washer Q', in which case the tension of both springs is brought into play for the purpose of producing stronger blows. When the washer Q' rests against the end of the mallet, the spring P is compressed between the end of the mallet R and the nut W. The weak spring Q is always in play, but the stronger spring P is not in play while the minimum soft blows are being used, because the blows are too light to affect the heavy spring, while they do affect the light spring. If a uniform blow is desired, the casing E may be provided with a series of perforations into which the spring-pin or catch upon the thumb-

slide will catch, and thus hold the thumb-slide in one position; or, if it is not desired to regulate the pressure of the springs by the thumb-slide, it may be done by applying a 70 knob or pin R' to the collar V, and have this knob or pin R' catch in a notched slot S, formed in the casing E. It is immaterial which method of regulating the springs is used.

The mallet R is made as heavy as it conveniently can be, and it is provided with the projections D', which serve to keep it out of actual contact with the casing E, and thus decrease the amount of friction between the 80 parts.

Inside of the casing E, just beyond the end of the mallet, is placed the tool-holder E', of the construction shown in Fig. 3, and placed in a groove in the inner end of this tool-holder is the L-shaped lever F', provided with a handle G', which projects through a slot or opening in the casing E. A portion of the head or inner end of the tool-holder E' is cut away, as shown, so as to form the shoulder H', 90 and the L-shaped portion of the lever F' projects down below this shoulder, as seen in Fig. 3. The end of the mallet R, when the instrument is not in use, does not touch the end of the lever F'; but when the operator 95 presses upon the handle G' the lever turns upon its fulcrum and the inner end of the lever is moved outward, so as to come in contact with the end of the mallet, and thus the mallet is instantly brought into operation. 100 The mallet can also be brought into operation by giving the tool-head an inward movement, so that when pressure is brought to bear upon the tool-point the pitman-shoulder will be moved into contact with the mallet. 105

In order to enable the same tools to be used in all parts of the mouth, a second tool-holder I' can be placed inside of the one E', and which tool-holder I' serves as an extension, so as to make the ordinary tools long enough to 110 operate upon the teeth in the back of the mouth, and thus do away with special long instruments for this purpose. Over the end of the tool-holder is placed a conical plug J', as shown in Fig. 1, and which projects beyond 115 the end of the case any suitable distance.

The cover L' (shown in Fig. 10) is provided with a notch N' in its inner end, and which notch catches over a projecting point of the spring T upon the partition S. A small lug A, 120 which projects from the casing E, also catches in the notch N', and prevents the cover from turning. The lug A and the projecting point of the spring hold the cover to the instrument, as shown in Fig. 10, the lug catches in the 125 corner of the notch or recess N', and the spring snaps into the recess as the cover is pushed on, and thus the cover is rigidly fastened to the casing E. When the cover is to be removed, the spring is pressed out of the 130 recess by the finger-nail, and then the cover can be drawn off. The mallet is prevented

from turning in the casing E, so that the slot Z is always in position to receive the wire Y. The tool-holder and the other portions are also prevented from revolving.

5 Having thus described my invention, I claim—

1. The combination of the casing E, the rod O, the head N, the pitman secured to the head and an operating mechanism with the springs P Q, washer Q', and the mallet provided with a recess to receive the spring Q, substantially as set forth.

2. In a dental plugger, the combination of the casing E, the mallet placed therein, the rod secured to the mallet at one end, the head secured to the other end of the rod, the two springs P Q, of unequal tension, placed upon the rod, a washer Q', loosely placed on said rod to separate the springs, the sleeve V, and 20 a regulating-nut W, substantially as specified.

3. The combination of the mallet having a recess formed in its end, the rod Q, a sliding collar placed on the rod, the springs P Q, and the washer Q', whereby the spring Q can be 25 forced into the recess, substantially as shown.

4. The combination of the mallet, the rod connected thereto, and the springs placed upon the rod with the tool-holder having an opening and a recess in its upper end and a 30 lever provided with an operating-arm which projects through the casing, and an angle-arm fulcrumed in the upper slotted end of the said holder, substantially as shown.

5. The combination of the casing E with

the mallet R, provided with the groove Z, and 35 the projections D', substantially as set forth.

6. The combination of the partition, the spring T, and lug A secured thereto, and the cover U, provided with a notch in which the end of the spring catches, substantially as set 40 forth.

7. The combination of the wheel F, having an opening through its center, the plate G, placed in the opening and provided with the pins H, and the screw which is passed through 45 the plate, substantially as specified.

8. The combination of the casing E, the rod O, the springs, the head N, the partition S, the mallet, the tool-holder, a lever fulcrumed upon the holder and which has its inner end 50 engage the mallet when depressed, the spring-pitman normally supported below the mechanism, and an operating mechanism for operating the pitman, substantially as shown.

9. The combination of the revolving wheel 55 F, with a stud or projection J, and a suitable mechanism for operating it, with a spring-pitman K, provided with a shoulder upon each side of its free end, whereby the wheel may be made to operate the plugger when re- 60 volved in either direction, substantially as set forth.

In testimony whereof I affix my signature in presence of two witnesses.

FREDERICK C. RIES.
